CLAIM

The ornamental design for a vacuum hose handle, as shown and described.

DESCRIPTION

FIG. 1 is a right side elevation view of a vacuum hose handle;

FIG. 2 is a left side elevation view thereof;

FIG. 3 is a front elevation view thereof;

FIG. 4 is a back elevation view thereof;

FIG. 5 is a top plan view thereof;

FIG. 6 is a bottom plan view thereof;

FIG. 7 is a back top right perspective view thereof;

FIG. 8 is a back bottom right perspective view thereof; and,

FIG. 9 is a back bottom left perspective view thereof.

The broken lines are for environmental purposes only and

form no part of the claimed design.

1 Claim, 5 Drawing Sheets
